(57) **CLAIM**

The ornamental design for a double bowl fryer tank, as shown and described.

DESCRIPTION

FIG. 1 shows a left perspective view of a double bowl fryer tank;

FIG. 2 shows a right perspective view thereof;

FIG. 3 shows a front view thereof;

FIG. 4 shows a left side view thereof;

FIG. 5 shows a right side view thereof;

FIG. 6 shows a bottom view thereof;

FIG. 7 shows a top view thereof with a Section line 8-8; and,

FIG. 8 shows a perspective, interior view, partially sectioned along line 8-8 of FIG. 7.

The broken lines shown in the drawings are for illustrative purposes only and form no part of the claimed design.
